United States Patent

Des. 239,800
Patented May 11, 1976

239,800

TABLE

Keith McDonald Roberson, Mecklenburg, N.C., assignor to Crowell-Roberson, Inc.

Filed Oct. 24, 1974, Ser. No. 517,503

Term of patent 14 years

Int. Cl. D6—03

U.S. Cl. D6—146

FIG. 1 is a perspective view of a table showing my new design;

FIG. 2 is a side elevational view thereof on a reduced scale;

FIG. 3 is a top plan view thereof also on a reduced scale; and

FIG. 4 is a perspective view of another embodiment of my new design.

I claim:

The ornamental design for a table, substantially as shown.
